The ornamental design for a sprinkler sleeve attachment, as shown and described.

DESCRIPTION

FIG. 1 shows a perspective view of a sprinkler sleeve attachment;

FIG. 2 shows a front view of the sprinkler sleeve attachment;

FIG. 3 shows a rear view of the sprinkler sleeve attachment;

FIG. 4 shows a right side view of the sprinkler sleeve attachment;

FIG. 5 shows a left side view of the sprinkler sleeve attachment;

FIG. 6 shows a top plan view of the sprinkler sleeve attachment; and,

FIG. 7 shows a bottom plan view of the sprinkler sleeve attachment.

The shaded lines in the Figures show contour and not surface ornamentation.

The broken lines shown represent portions of a sprinkler sleeve attachment and form no part of the claimed design.

1 Claim, 4 Drawing Sheets(56)
